Primary Examiner — Austin Murphy(74) *Attorney, Agent, or Firm* — Karen B. Tripp(57) **CLAIM**

The ornamental design for an identification card scanner, as shown.

DESCRIPTION

FIG. 1 is a perspective view of a identification card scanner, showing my new design.

FIG. 2 is a top view of the scanner of FIG. 1.

FIG. 3 is a bottom view of the scanner of FIG. 1.

FIG. 4 is a left side view of the scanner of FIG. 1.

FIG. 5 is a right side view of the scanner of FIG. 1.

FIG. 6 is a front view view of the scanner of FIG. 1.

FIG. 7 is a back view view of the scanner of FIG. 1; and, FIG. 8 is a perspective view of the scanner of FIG. 1 including an identification card for demonstration purposes and shown in dotted lines to indicate that the identification card is not part of the design.
